J. J. CAIN.

METHOD OF MAKING FLANGED ARTICLES.

APPLICATION FILED APR. 30, 1918. RENEWED SEPT. 18, 1919.

1,338,419.

Patented Apr. 27, 1920.

By his Attorney

John J. Cain

Alfred Shedlock.

UNITED STATES PATENT OFFICE.

JOHN J. CAIN, OF BAYONNE, NEW JERSEY.

METHOD OF MAKING FLANGED ARTICLES.

1,338,419.

Specification of Letters Patent. Patented Apr. 27, 1920.

Application filed April 30, 1918, Serial No. 231,664. Renewed September 18, 1919. Serial No. 324,576.

To all whom it may concern:

Be it known that I, JOHN J. CAIN, a citizen of the United States, residing at Bayonne, county of Hudson, State of New Jersey, have invented new and useful Improvements in Methods of Making Flanged Articles, of which the following is a specification.

This invention relates to flanged articles, that is cup or trough shaped vessels, with 10 the flanges or walls integral with the bottoms or main portions, formed from suitable blanks of sheet metal. In the manufacture of such articles by a drawing, stamping or folding process the metal at the angles of 15 walls and bottoms is, by stretching, distorted or reduced in thickness and the walls are often thinner than the bottoms, which retain the initial thickness of the sheet metal.

20 The object of this invention is to restore the metal at the angular bends and in the walls to normal thickness, whereby uniformity of strength is had in all parts of the vessels, or to increase the thickness of the 25 bends and walls beyond the normal thickness of the metal, thereby increasing the resistance of the same to pressures and rough usage and providing more metal for subsequent manipulations or mechanical operations.

30 This is accomplished by applying pressure to the edges of the walls after they are formed, and preferably while the articles are held in the forming dies or molds. The method also provides for shaping the 35 edges of the walls and forming the bottoms of such articles to adapt them for special purposes.

It is essential in the practice of this method that the sheet metal be sufficiently 40 pliable and plastic to flow under pressure applied as set forth. If the metal be hard and insufficiently pliable for manipulation under this method, as iron and steel, it may by heating in suitable furnaces be brought 45 to the requisite pliable and plastic condition.

Broadly, therefore, the invention consists in changing the walls and other parts of flanged articles by pressure applied to the 50 edges of the walls, as hereafter fully set forth, reference being had to the accompanying drawings, in which:

Figure 1. represents a vessel, in section, showing distortion or thinning of the angular bends due to the action on sheet metal of the flange forming operation.

Fig. 2. illustrates the same vessel with the angular bends thickened or restored to the normal thickness of the metal, by pressure applied to the edges of the flanges or sides 60 of the vessel, said edges being thereby somewhat shortened.

Fig. 3. is a similar view with the flanges or walls also thickened, their height being proportionately reduced, as indicated. 65

Fig. 4. shows a blank of sheet metal suitable for forming a special article according to this invention.

Fig. 5. is a longitudinal section of the article completely formed. 70

Fig. 6. is a plan view of the same.

Fig. 7. is a transverse section, showing the first stage of the formation of the article, with the walls bent or formed up from the bottom. 75

Fig. 8. is a transverse section on line 8, 8, Fig. 5, showing the walls and bends thicker than the bottom, which retains substantially the thickness of the sheet metal blank.

Fig. 9. illustrates, conventionally a press 80 or apparatus provided with dies, formers &c. adapted to make the article shown in Figs. 5 to 8, and:

Fig. 10. is an end view of the same, showing the dies &c. in section, as indicated by 85 line 10, 10 Fig. 9.

It will be understood that suitable special dies &c. will be provided to manufacture different forms and styles of flanged articles, and that to facilitate the manufacture 90 of such articles under this invention the walls will preferably be thickened and the articles otherwise shaped, by pressure applied to the edges of the walls, as soon as the walls are formed and while the articles are 95 held in the forming dies.

Fig. 1, illustrates a flange or cup shaped article, in section, as ordinarily made of sheet metal; 11, designating the bottom and 12 the walls, showing a distortion or stretching of the angular bends 13. These angular bends may under the operation of the method of this invention be restored to the normal thickness of the sheet metal, or increased beyond the normal thickness of the metal, as shown at 14, Fig. 2, the sides 12, being thereby somewhat shortened. The walls, by a continuance of the pressure on their edges, may be increased in thickness to any desired extent, being correspondingly decreased in height, as shown at 15, Fig. 3. During the time pressure is applied 105 110

to the edges of the walls the articles will be held in suitable dies or molds that surround the walls and determine the sizes and shapes of the walls.

5 In practising this invention special dies, &c., will be provided, operated in a suitable press, such as a hydraulic press illustrated in Figs. 9 and 10, in which 16, is the cylinder; 17, the ram; 18, the platen and 19, the base. The female die or mold 20, seated on the base 19, will have the shape of its cavity conform to the outside of the finished article being made. The movable die comprises a plunger 21, shaped in accordance with the 10 interior of the article and a flange compressor 22, attached to the platen 18, and surrounding the plunger. This flange compressor is adapted to fit in the space between the walls of the cavity of the mold 20, and 15 the sides of the plunger 21. The plunger 21, is free to slide in the flange compressor 22, and partly in the platen 18, said platen being provided with pawls or dogs 23, adapted, by 20 acting on the top of the plunger to hold it 25 in outer position relatively to the flange compressor; see Fig. 10. Pins 24, extending from the platen 18, into slots formed in the ends of the plunger causes the plunger to move upwardly with the platen. Assuming 30 the parts to be in the positions shown: a sheet metal blank 26, in proper working condition, is placed over the mold 20, and the platen 18, is caused to descend until the blank is forced to the bottom of the mold, or 35 to a suitable desired position in the mold, the distance from the bottom of the plunger and the edges of the flange compressor being then sufficient to permit the side walls of the article, when folded up, to lie against 40 the sides of the plunger beneath the edges of the flange compressor. The dogs 23, are now removed from the top of the plunger 21, and, by a further downward movement of the platen, the flange compressor moves 45 down the plunger to act on the top of the side walls of the article causing the metal of said walls to flow both laterally and downwardly to fully fill the spaces between the plunger 21, and the sides of the cavity 50 in the mold if the initial movement of the plunger has carried it the full distance in the mold; if the article is of such a character that the plunger and flange compressor must travel together to complete it then the 55 upper side of the opening in the platen by acting on the top of the plunger will cause it to shape the bottom of the article at the same time the flange compressor is shaping the walls. Reversal of movement of the 60 ram 17, upon completion of the operation, will first raise the flange compressor 22, and then, by the pins 24, striking the upper ends of the slots 25, draw the plunger 21, out of the mold with the formed article on it, from 65 which it may be detached by a stripper, not

shown in the drawings; such devices being well known and common to all kinds of presses.

In making flanged articles, as rectangular troughs, such as at Figs. 5 to 8, it may be 70 advantageous to shape the blanks from which they are formed, as for instance by cutting away the corners, see 27, Fig. 4, to facilitate the folding up of sides 28 and ends 29, to make the right angular bends with the 75 bottom 30. Such a trough shaped article can be made by the forming devices shown in Figs. 9 and 10 in the manner before described. The sides 28 and ends 29 are bent up during the first action of the plunger 21, 80 on the blank 26, which is set over the mold or female die 20, the plunger forcing the bottom 30, in the die until it is in contact with or slightly depressed in the corrugated bottom 31, by the corrugations 32, at the 85 bottom of the plunger 21. The edges of the flanged compressor 22, which has similar corrugations 33, then act on the tops of sides 28 and ends 29, causing them to fill the 90 spaces between the plunger and sides of the mold, thereby thickening said side and end walls, as shown in Fig. 8, and at the same time shaping the corrugations in the bottom 30, and correspondingly shaping the edges 95 of the walls 28, as shown in Fig. 5.

This particular trough like article Figs. 5 and 6, is adapted for use in making headers for tubular boilers; for which purpose they are arranged in pairs with the edges of the walls adjacent, said edges then being 100 securely welded together. The headers are completed by welding the joints at the sides of the ends 29 and the ends of the sides 28, and making the tube holes and hand holes in the sides 28, which constitute the front and 105 back walls of the header. Such headers are fully described and claimed in an application filed by me simultaneously herewith under Serial No. 231,663.

I claim:

1. The method of making flanged articles, which consists in first forming up the flanges or sides from a sheet metal blank and then by pressure applied to the edges of the flanges or sides, with the article held in 115 a shaping mold, restoring the bends at the angles of the sides and body, stretched or distorted by the forming process, to the normal thickness of the metal.

2. The method of making flanged articles, 120 which consists in first forming up the flanges or sides from a sheet metal blank and then by pressure applied to the edges of the flanges or sides, with the article held in a shaping mold, increasing the thickness of 125 the flanges or sides and correspondingly decreasing the height of the same.

3. The method of making flanged articles, which consists in first forming the flanges or sides from a sheet metal blank, then thick- 130

ening the bends at the angles of the sides and bottom and increasing the thickness of the sides and correspondingly decreasing the height of the same by pressure applied to 5 all parts of the free edges of the sides, with the article held in a shaping mold.

4. The method of making flanged articles, which consists in first forming the flanges or sides from a sheet metal blank and then 10 by pressure applied to the edges of the sides, with the article held in a shaping mold, changing the contour of said edges and increasing the thickness of the sides and correspondingly decreasing their height.

15 5. The method of making flanged articles, which consists in first forming the flanges or sides from a sheet metal blank, then forming depressions or corrugations in the bottom or main portion of the article, correspondingly changing the contour of the 20 edges of the sides, by pressure applied thereto, with the article held in a shaping mold, and at the same time thickening the sides and conformably decreasing their height.

25 6. The method of making flanged articles, which consists in first forming the sides and ends from a sheet metal blank, then forming

depressions or corrugations in the bottom of the article and then by pressure applied to the edges of the sides and ends, with the 30 article held in a shaping mold, restoring the angular bends, which are distorted or stretched by the forming process, to the normal thickness of the metal, thickening the sides and ends and shaping the edges of the 35 sides to correspond with the contour of bottom.

7. The method of making flanged articles, which consists in first forming the sides and ends from a sheet metal blank, then forming 40 depressions or corrugations in the bottom of the article, simultaneously correspondingly changing the contour of the edges of the sides thus forming recesses in the edges of the sides at the concave and 45 convex parts of the corrugations by pressure applied to said edges, with the article held in a shaping mold.

Signed at New York, county and State of New York, this 24 day of April, 1918.

JOHN J. CAIN.

In the presence of—

JOHN J. HAYDEN,
JAMES A. HUDSON.
